PLATEN PRINTING PRESS

Lawrence R. Johnson, Cleveland, Ohio, assignor to
 The Chandler & Price Company, Cleveland,
 Ohio, a corporation of Ohio

Application October 25, 1934, Serial No. 749,933

7 Claims. (Cl. 271—56)

This invention relates, as indicated, to printing presses of the Gordon or platen type, but has reference more particularly to presses of this type which are provided with pneumatic suction devices for feeding sheets to and delivering them from the platen of the press.

Suction devices of the aforesaid character usually include oscillatable tubular arms provided with sucker tip assemblies adapted to engage or contact the sheets and valves for periodically breaking the vacuum in the arms and sucker tips when suction is not desired.

Occasionally, a sheet which is to be removed from the platen by the delivery sucker tips is torn or otherwise mutilated so that it will not be engaged by one or more of the sucker tips. This leaves the delivery suction line open to the atmosphere so that the sheet in question will probably fall back onto the platen. In order to prevent injury to the type form and other parts of the press, it is customary in such cases to manually stop the press and remove the defective sheet or sheets before re-starting the press. The starting and stopping of a press not only results in a loss of time, but causes a strain on various parts of the press, besides the loss of electrical energy in starting, which, in the case of a large heavy press, is an item of considerable expense.

The present invention has as its primary object the elimination of the foregoing difficulties and disadvantages by the provision of means responsive to the failure of the vacuum in the sheet-removing means for breaking the vacuum in the sheet-feeding means, so that the feeding of the sheets will be discontinued, but the press will continue in operation. Another object of the invention is to provide means responsive to the breaking of the vacuum in the sheet-feeding means for throwing into operation the throw-off lever of the press.

To the accomplishment of the foregoing and related ends, said invention, then, consists of the means hereinafter fully described and particularly pointed out in the claims; the annexed drawings and the following description setting forth in detail certain mechanism embodying the invention, such disclosed means constituting, however, but two of various mechanical forms in which the principle of the invention may be used.

In said annexed drawings:

Fig. 1 is a fragmentary side elevation of a Gordon or platen type printing press embodying the invention;

Fig. 2 is a front elevation of the mechanism for breaking the vacuum in the feed line;

Fig. 3 is a side elevation of the mechanism shown in Fig. 2;

Fig. 4 is a horizontal cross-sectional view, taken on the line 4—4 of Fig. 2 and showing the normal

position of the plunger which breaks the vacuum in the feed-line;

Fig. 5 is a horizontal cross-sectional view, similar to Fig. 4, but showing the plunger in position to break the vacuum in the feed line;

5

Fig. 6 is a more or less diagrammatic view showing the arrangement of the various suction lines;

Figs. 7 and 8 are views similar to Figs. 2 and 3 respectively, but showing a modified form of the invention.

A printing press of the Gordon or platen type includes, as indicated in Fig. 1, a frame 1, in which is journaled the main shaft 2 having mounted on one end the large gear cam wheel 3 which is adapted to oscillate the platen (not shown) between sheet-receiving and printing positions.

The press also includes sheet-feeding and delivery mechanism, the suction line to the feeding mechanism being indicated by the numeral 4 in Fig. 6, such suction line being connected to one side of a double-acting vacuum pump 5, whereby the necessary suction is provided in said line.

The sheet feeding mechanism is disclosed in Root Patent No. 1,969,946, granted Aug. 14, 1934. 25

The sheet delivery mechanism is disclosed in some detail in Fig. 1, and includes a sucker tip assembly 6 which is connected to a hollow arm 7, in which suction is maintained by means of the pump 5, through the intermediary of a suction line 8 connected to the other side of the pump 5 and an off-take conduit 14' branching from line 8.

The arm 7 is adapted to be moved in such a path as to cause the sucker tips to engage a printed sheet on the platen, recede from the platen, deposit the sheet on a delivery table and return to the platen for the next sheet. The necessary movement, a combined oscillatory and reciprocatory movement, is imparted to the arm 7 by means of cams 9 and 10, which are mounted on a shaft 11, this shaft being rotated by and in synchronism with the wheel 3. During the recession of the sucker tips, the lower end of the arm 7 moves downwardly to the position indicated by the dotted lines in Fig. 1. For the purpose of the present invention, this downward movement of the arm 7 is the principal feature in connection with the delivery mechanism, which it is essential to bear in mind.

It will be understood that suction is to be maintained in the feeder sucker tips only during the feeding of the sheet from the feed table to the platen and in the delivery sucker tips only during the delivery of the printed sheet from the platen to the delivery table. At all other times the partial vacuum in lines 4 and 8 is broken by opening these lines to the atmosphere. This is accomplished in the following manner.

The conduit 4 communicates with the atmosphere through conduits 12 and 13, and conduit

50

55

45

40

40

50

55

60

8 communicates with the atmosphere through conduits 14 and 15. When suction is desired in the sucker tips, the conduits 13 and 15 are respectively closed to the atmosphere by means of 5 tappet valves 16 and 17, which are spring-pressed to the conduit-closing position by means of a tension spring 18, which is secured at one end to a lever 19 upon which the tappets are mounted and at the other end to a lever 20. Lever 20 is 10 secured to a trip lever 21, the function of which will be presently described.

The lever 19 is rigidly secured to one end of a pin 22, which is journalled in a bracket 23 mounted on an extension of the press frame 1. Secured to the opposite end of the pin 22 is a 15 lever 24 provided at one end with a roller 25. This roller engages a cam 26 on the wheel 3. It will be apparent from Fig. 1 that rotation of the cam 26 will periodically lift the tappets off the 20 conduits 13 and 15, so as to open these conduits to the atmosphere and break the vacuum in the feed and delivery sucker tips.

Occasionally, a sheet which is to be removed from the platen by the sucker tips is torn or 25 otherwise mutilated so that it will not be engaged by one or more of the sucker tips. This leaves the delivery suction line open to the atmosphere, so that the sheet in question will probably fall back on the platen. In order to prevent 30 injury to the type form and other parts of the press, it is customary in such cases to manually stop the press and remove the defective sheet or sheets before re-starting the press. The starting and stopping of a press not only results in a loss 35 of time, but causes a strain on various parts of the press, besides the loss of electrical energy in starting, which, in the case of a large, heavy press, is an item of considerable expense.

In order to avoid these difficulties and disadvantages, I have provided mechanism whereby, when a failure of vacuum in the delivery line takes place, as in the manner above described, the vacuum in the feed line will be also automatically broken.

45 For this purpose, there is secured to the conduits 13 and 15 a housing 27, the conduits extending through the housing as clearly shown in Fig. 4. The conduits 13 and 15 are respectively provided with openings 28 and 29, which are in 50 registration with passages 30 and 31 in the housing. The passages 30 and 31 are in communication with a cylindrical bore 32, the axis of which is transverse to those of the passages 30 and 31. A port 33 in the housing which is disposed opposite the passage 30 is in communication 55 with the atmosphere.

Slidably mounted within the bore 32 is a plunger or valve 34 having a socket 35 in one end adapted to receive a coil spring 36, this 60 spring abutting the housing and the plunger. This plunger is provided with two portions 37 and 38 of a diameter substantially equal to that of the bore 32 and with portions 39 and 40 of reduced diameter, the junction of portions 37 and 65 39 forming a shoulder 41, and the junction of portions 38 and 40 forming a shoulder 42. The plunger is provided at its outer end with a knurled portion 43 whereby the plunger may be pushed into the housing.

70 The housing 27 is provided with a rearwardly extending arm or bracket 44, to which is pivotally secured the lever or latch 21 and a second gravity-operated latch 45 is also provided, which is pivotally secured to the housing, as by means 75 of a pivot screw 46.

When the sucker tips of the delivery mechanism are functioning in a normal manner, the vacuum in the conduit 15 is sufficiently great to maintain the plunger 34 in the position shown in Fig. 4, in which position the spring 36 is compressed and the portion 38 of the plunger seals the passage 30 and port 33, thereby maintaining the vacuum in the feed conduit. When the tappet 17 is lifted so as to open the conduit 15 to the atmosphere, the plunger 34, which would under these conditions be pushed out of the bore 32 by the spring 36 to the position shown in Fig. 5, is prevented from being so moved, by virtue of the latch 21 which engages the shoulder 41 of the plunger at these intervals. It will be understood that the latch 21 is periodically moved downwardly to the plunger-releasing position whenever the lever 20 is pulled downwardly by the engagement of the arm 7 with the lower hooked end of the lever, but the vacuum in conduit 15 is sufficient at such periods to hold the plunger in the position shown in Fig. 4.

Should a torn or mutilated sheet be placed on the platen and one of the sucker tips fail to make proper contact with such sheet, the vacuum in the conduit 15 will be broken, and will no longer be effective to maintain the plunger 34 in position to seal the feed conduit 13 from the atmosphere. Consequently, when the lever 20 is pulled downwardly by the lower end of arm 7 during the receding movement of the sucker tips 6 from the platen, the latch 21 will be pulled downwardly and the spring 36 will force the plunger 34 to the position shown in Fig. 5, the plunger being stopped and maintained in this position by the engagement of the gravity latch 45 with the shoulder 42 of the plunger. When in this position, the feed conduit 13 is open to the atmosphere and the vacuum therein is broken. Feeding of the sheets to the platen 40 will therefore be discontinued.

Although the feeding and delivery of the sheets are thus discontinued, the press will continue in operation. As a further precaution and to avoid possible injury to the platen or form of the press while it thus continues in operation, means have also been provided to automatically move the throw-off lever of the press into operation when the vacuum in the feed line 4 is broken. Such means is diagrammatically shown in Fig. 6, and includes a suction conduit 50, which communicates with the conduit 4. The throw-off lever 51 is pivotally mounted on a stub shaft 52 which extends from the frame of the press and has a longitudinal passageway 53 which communicates with the conduit 50. A short radially extending passageway 54 in the shaft 42 communicates with the passageway 53 and with a passage 55 in the throw-off lever. The passage 55 extends to a cylindrical bore 56 of larger diameter than passage 55, and slidably mounted in this bore is a plunger 57. A coil spring 58 within the bore abuts the upper end of this plunger.

A bell-crank lever 59, which is pivotally mounted on the throw-off lever, has one of its arms pivoted to the lower end of the plunger 57 and has secured to its other arm a pin 59, which passes through an aperture in the lower end of the throw-off lever.

In the normal operation of the press, the suction in the conduit 50 is sufficient to overcome the action of the spring 58 and maintain the plunger 57 and pin 59 in the position shown in Fig. 6. When, however, the vacuum in conduit 50 is broken, as in the manner above described, 70 75

the plunger 57 will drop and cause the pin to enter a slot 60 in a bar 61. Bar 61 is pivotally secured to the bed of the press and is reciprocated as the bed oscillates. The bar, in its reciprocating movement, slides on the connecting link 62 which is pivotally connected to the lower end of the throw-off lever and to the throw-off mechanism. Consequently, when the pin enters the slot 60, the throw-off lever will be oscillated, that is, thrown into operation. It will be understood that by throwing the throw-off lever into operation is meant that the back-shaft of the bed is alternately oscillated by the throw-off lever in such a manner that the bed will not contact the platen on the printing stroke of the bed.

As previously stated, the press, after breakage of the vacuum in the feed line, will continue in operation, and the operator, in order to resume the printing operations, needs only to remove the defective sheet or sheets, and push the plunger 34 back to the position shown in Fig. 4, whereupon the feeding and delivery of the sheets will be resumed. Resumption of suction in conduit 4 will likewise result in resumption of the suction in conduit 50, so that the pin 59 will be drawn out of the slot 60 and the throw-off lever may then be moved to its impression or printing position.

In that form of the invention shown in Figs. 7 and 8, the lifting of the tappet 16 is utilized to open the feed conduit 13 to the atmosphere in case of failure of the delivery mechanism to remove the sheet from the platen. In order to thus lift the tappet 16, the following mechanism is provided. The delivery conduit 15 has secured thereto a housing 70 in which is provided a passageway 71 which communicates with the interior of conduit 15 and with a vertically extending passage, in which is mounted a plunger 72. The lower end of the plunger is in abutment with a spring 73, and its upper end is pivotally connected with a trip lever 74 which is pivotally mounted on the housing 70. The lever 74 has a heel portion 75 under which a trip arm 76, mounted on a lever 77, is adapted to be positioned. The lever 77 is pivoted as at 78 to the housing 70 and is also pivotally connected to the lever 20, a tension spring 79 interconnecting the lever 19 with the point of pivotal connection of link 77 and lever 20.

Downward movement of the lever 20 in the normal operation of the press has the effect of periodically withdrawing the trip arm 76 from its position under the heel 75 of the trip lever, but the suction in conduit 15 at such times is sufficient to overcome the action of spring 73, so that the trip lever 74 remains in the position shown in Fig. 8, and the movement of the tappets 16 and 17 is not interfered with. In case of breakage of the vacuum in conduit 15, as previously described, the plunger 72 will be urged upwardly by the spring 73, with the result that the trip lever is caused to underlie an abutment 80 on the lever 19, thus holding both tappets 16 and 17 in raised position. This will, of course, take place when the trip arm 76 is out of the position in which it underlies the heel 75 of the lever 74.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. In a printing press of the Gordon type, pneumatic suction means for feeding sheets to the platen of said press, pneumatic suction means for removing said sheets from the platen of said press, and means responsive to failure of the vacuum in the sheet-removing means for automatically breaking the vacuum in the sheet-feeding means. 5

2. In a printing press of the Gordon type, pneumatic suction means for feeding sheets to the platen of said press, pneumatic suction means for removing said sheets from said platen, and means responsive to failure of the vacuum in the sheet-removing means during movement of such means away from the platen for automatically breaking the vacuum in the sheet-feeding means. 10 15

3. In a printing press of the Gordon type, pneumatic suction means for feeding sheets to the platen of said press, pneumatic suction means for removing printed sheets from said platen, a vacuum being maintained in said last-named means only during the process of removal of said sheets from said platen, and means responsive to 20 25 a failure of the vacuum in one of said means for automatically breaking the vacuum in the other of said means.

4. In a printing press of the Gordon type, pneumatic suction means for feeding sheets to the platen of said press, pneumatic suction means for removing said sheets from said platen, a vacuum being maintained in said last-named means only during the process of removal of said sheets from 30 35 said platen, and means responsive to a failure of the vacuum in said last-named means for automatically breaking the vacuum in the sheet-feeding means.

5. In a printing press of the Gordon type, pneumatic suction means for feeding sheets to the platen of said press, pneumatic suction means for removing said sheets from said platen, conduits leading from each of said means and normally open to the atmosphere, tappets for closing said conduits at predetermined intervals, and means 40 45 responsive to failure of the vacuum in that conduit leading from the sheet-removing means for automatically opening the other conduit to the atmosphere.

6. In a printing press of the Gordon type, pneumatic suction means for feeding sheets to the platen of said press, pneumatic suction means for removing said sheets from said platen, conduits leading from each of said means and normally open to the atmosphere, tappets for closing the 50 55 respective conduits at intervals when suction is desired in said feeding and removing means, and valve means responsive to the failure of the vacuum at such intervals in that conduit leading from the sheet-removing means for automatically opening the other conduit to the atmosphere irrespective of whether the tappet for said other conduit is in open or closed position.

7. In a printing press of the Gordon type, pneumatic suction means for feeding sheets to the platen of said press, pneumatic suction means for removing said sheets from said platen, conduits leading from each of said means to the atmosphere, tappets for closing said conduits at predetermined intervals, and means responsive to 60 65 failure of the vacuum in that conduit leading from the sheet-removing means for maintaining both tappets in open position. 70
